(57) **CLAIM**

The ornamental design for a partial top portion of a vehicle, toy, replica and/or other replicas, as shown and described.

DESCRIPTION

This application contains subject matter related to the following co-pending U.S. applications: application Ser. No. 29/311,512, entitled “Vehicle, Toy, or Likeness Thereof”; and application Ser. No. 29/311,510, entitled “Rear Portion of a Vehicle, Toy, or Likeness Thereof”.

FIG. 1 is a left, front perspective view of a partial top portion of a vehicle, toy, replica and/or other replicas according to my novel design, the right, front perspective view being mirror symmetrical;

FIG. 2 is a left, rear perspective view thereof, the right, rear perspective view being mirror symmetrical;

FIG. 3 is a rear view thereof;

FIG. 4 is a left side view thereof, the right side view being mirror symmetrical; and,

FIG. 5 is a top view thereof.

The broken lines are for illustrative purposes only and form no part of the claimed design.
